US00D875838S

(12) **United States Design Patent** (10) Patent No.: **US D875,838 S**
(45) Date of Patent: **** Feb. 18, 2020**

(54) **GAMING MACHINE TOPPER**

(71) Applicant: **Aristocrat Technologies Australia Pty Limited**, North Ryde, NSW (AU)

(72) Inventors: **Bruce Edward Urban**, Las Vegas, NV (US); **James Franklin Stair**, Las Vegas, NV (US); **William Douglas Lamb**, Eagleville, TN (US); **Dominic J. DeMarco**, Round Rock, TX (US); **Ariel David Turgel**, San Francisco, CA (US); **Dan Harden**, Palo Alto, CA (US)

(73) Assignee: **ARISTOCRAT TECHNOLOGIES AUSTRALIA PTY LIMITED**, North Ryde, NSW (AU)

(**) Term: **15 Years**

(21) Appl. No.: **29/680,438**

(22) Filed: **Feb. 15, 2019**

CLAIM

We claim the ornamental design for a gaming machine topper, as shown and described.

DESCRIPTION

FIG. 1 is a front perspective view of a gaming machine topper showing our new design;

FIG. 2 is a front view of the gaming machine topper shown in FIG. 1;

FIG. 3 is a back view of the gaming machine topper shown in FIG. 1;

FIG. 4 is a right view of the gaming machine topper shown in FIG. 1;

FIG. 5 is a left view of the gaming machine topper shown in FIG. 1;

FIG. 6 is a top view of the gaming machine topper shown in FIG. 1; and,

FIG. 7 is a bottom view of the gaming machine topper shown in FIG. 1.

Broken lines illustrate unclaimed environmental features and form no part of the claimed design.

1 Claim, 7 Drawing Sheets
